UNITED STATES PATENT OFFICE.

GUSTAVE HOLTER, OF SEATTLE, WASHINGTON.

VALVE.

Application filed February 18, 1925. Serial No. 9,973.

To all whom it may concern:

Be it known that I, GUSTAVE HOLTER, a citizen of the United States, residing at Seattle, in the county of King and State of Washington, have invented a certain new and useful Improvement in Valves, of which the following is a specification.

My invention relates to new and useful improvements in valves that are particularly adapted for controlling the flow of liquids through pipes wherein hydraulic pressure is maintained, and the principal objects of my invention are to provide a valve that is adapted to be normally held in a closed position by hydraulic pressure and which may be manually opened by turning a valve handle.

Further objects are to provide a valve having a pressure chamber with a conduit connection wherein an inner tube extends upwardly into a cup member of the valve and whereby fluid pressure is forcibly and directly brought into engagement with said valve to hold the same against its seat.

Still further objects are to provide a valve that is simple and durable in construction, reliable and efficient in operation and which is entirely free of all springs, gaskets or packings.

With the above and other objects in view which shall appear as the description proceeds, my invention consists of novel construction, adaptation, arrangement and combination of parts hereinafter described by devices illustrated in the accompanying drawings, wherein—

Figure 1 is a view in central vertical section of a faucet showing the valve in the open position;

Fig. 2 is a view partly in elevation and partly in vertical showing the valve in a closed position;

Fig. 3 is a view in horizontal section taken on a broken line 3, 3 of Fig. 1; and

Fig. 4 is a detail view in elevation of the valve proper.

Referring to the drawings throughout which like reference numerals designate like parts, the numeral 5 indicates the base portion of a faucet that is provided with a depending reduced threaded portion 6 adapted to be secured to a conduit or supply pipe. An inner pipe 7 is threadedly secured within said reduced portion and projects upwardly into a pressure chamber 8 provided within said base portion. A wire screen 9 is inter-

posed within said inner pipe and an opening 10 is provided therein for draining said pressure chamber as will be readily understood.

The base portion 5 is threadedly secured at its upper end to a valve casing 11 that is provided with a discharge nozzle 12 communicating with an interior chamber 13 of said valve casing. Said interior chamber is provided with a lining 14 fixedly secured therein and beveled at its lower open end to form a valve seat 15.

A valve 16 is slidably mounted within the chamber 13. The upper portion of said valve comprises a plurality of vertical ribs 17 in spaced relation with a central spline 18 and is therefore adapted for the free passage of fluids.

The lower portion of the valve is made in the shape of an inverted cup 19 adapted to fit over the upper end portion of the pipe 7 with sufficient space between for the free passage of liquid. The conical section, as designated by the numeral 20, between the upper and lower portions of said valve is arranged to engage the seat 15 as will be readily understood. It will now be apparent that the hydraulic pressure within the chamber 8 will hold the valve in a normally closed position as clearly shown in Fig. 2 of the drawings. The pressure is brought directly and forcibly upwardly within the cup 19.

The means for manually operating the valve comprises a valve stem 21 provided at its upper end with a handle 22 and at its lower end with a worm portion 23 threadedly mounted within the casing 11 and whose lower extremity is adapted to functionally engage the top of the valve 16.

The upper end of the casing 11 is reduced and threaded to receive a cap 24. A recess 25 is provided within said upper end and is internally threaded to receive a nipple 26 that fits snugly around the stem 21. Said nipple is provided with diametrically disposed slots 27 adapted to receive a key or other instrument for the purpose of turning the nipple and thus adjusting the movement of said valve stem.

The stem 21 is provided with a reduced portion and two half rings 28 are arranged to fit therein and to ride up and down with said stem. Said half rings will abut against the floor of the recess 25 at the limit of their downward movement and at the limit of their upward movement they will engage the nipple 26. It will be obvious that the

throw of said stem may be regulated by turning said nipple.

Referring to Fig. 2 of the drawings, as hereinbefore stated, the action of the fluid within the chamber 8 and pipe 7 in pressing upwardly against the cup 19 will hold the valve in a normally closed position. By turning the handle 22 in a counter clockwise direction the lower extremity of the stem 21 will push the valve downwardly to the open position shown in Fig. 1 and the fluid will pass freely through said valve and will continue to discharge through the nozzle 12 as long as said handle is held in this position. By turning the handle 22 in the reverse direction to raise said stem the pressure of the liquid will again cause said valve to immediately follow said stem upwardly as will be readily apparent. The peculiar design of the upper portion of said valve will serve to disseminate the force of the water in its discharge.

What I claim is:

1. A valve slidably mounted within a cas-

ing, the upper portion of said valve comprising a plurality of ribs in spaced relation, a cup member for the lower portion of said valve, an inner tube projecting within said member and said valve adapted to be held in a normally closed position by hydraulic pressure acting through said tube against said cup member.

2. A valve slidably mounted within a casing, a valve seat within said casing, a pressure chamber within said casing, drainage means for said pressure chamber, a tube projecting into said pressure chamber, a plurality of ribs disposed in spaced relation upon the upper portion of said valve, and a conical portion disposed upon the lower portion of said valve and adapted to be held in normal engagement with said valve seat when a pressure is exerted against the bottom portion of said valve.

In witness whereof, I hereunto subscribe my name this 11th day of February A. D. 1925.

GUSTAVE HOLTER.
